UNITED STATES PATENT OFFICE.

SIGMUND BERGMANN, OF NEW YORK, N. Y., ASSIGNOR TO THE BERGMANN ELECTRIC AND GAS FIXTURE COMPANY, OF SAME PLACE.

EXTENSION-FIXTURE FOR GAS OR LAMPS.

SPECIFICATION forming part of Letters Patent No. 426,163, dated April 22, 1890.

Application filed September 7, 1889. Serial No. 323,309. (No model.)

To all whom it may concern:

Be it known that I, SIGMUND BERGMANN, of New York, in the county and State of New York, have invented a certain new and useful Improvement in Extension-Fixtures for Gas or Lamps, of which the following is a specification.

The invention consists in the construction and novel arrangement of parts as hereininafter specified. Heretofore in extension-fixtures of this character where a friction-spring is employed a clutch mechanism has been employed. This is objectionable, as it adds greatly to the cost of the fixture, and is liable by sudden movement to break the spring and render the device useless. In my device no clutch is employed, and the block through which the tube slides has no vertical movement, and its ends bear against the ends of its chamber.

In the accompanying drawings, Figure 1 is a longitudinal section and partial elevation of the device embodying my invention, and Fig. 2 is a plan view with the chamber-cap removed.

Similar letters of reference designate corresponding parts in both figures.

Referring by letter to the drawings, A designates the extension or sliding tube, intended to carry a gas-burner or lamp-holder at its lower extremity, and B is a fixed tube into which the tube A slides. The tube A is angular in cross-section, and is twisted or formed with spiral ribs to engage with and rotate the block C, which has a longitudinal opening through it corresponding to the form in cross-section of the tube A.

D is a barrel secured to the lower end of the tube B, and having a central opening for the passage of the tube A. This barrel D provides a chamber d for the block C and the flat spring e, which has one end rigidly secured to the block, and its free portion laps around the block and has a frictional bearing against the wall of the chamber d. A cap a removably engages, by a screw-thread or otherwise, the lower end of the barrel D, and

has an opening through which the tube A slides.

The length of the block C is such that its ends abut against the inner wall of the barrel and the inner face of the cap, so that the block has no vertical play or movement to change the tension of the spring.

In operation, when the tube A is drawn downward, the block C is revolved with the spring in such direction that the spring is wound so that its friction is increased on the wall of the chamber. It is evident that the tube A may be stopped and held at any desired point. In pushing the tube A upward the block C is rotated and the tension of the spring is relaxed, and the movement is quite easy.

The upper end of the tube A may be provided with any suitable packing to prevent escape of gas.

What I claim as my invention, and desire to secure by Letters Patent, is—

1. In an extension-fixture, the combination, with a fixed tube and a spiral sliding tube angular in cross-section, of a barrel on the lower end of the fixed tube, providing a chamber, a cap for said barrel, a rotary block within the chamber surrounding the sliding tube and rotated by the tube in its upward and downward movement, and a friction-spring secured to the block, substantially as specified.

2. In an extension-fixture, the combination, with the fixed tube and the sliding tube, of the barrel on the end of the fixed tube, providing a chamber, a cap for said barrel, a rotary plug surrounding and engaging with the sliding tube within the chamber, a spring secured to said plug and having a frictional bearing on the wall of the chamber, the said plug having a length equal to the length of the chamber, so that it has no vertical movement, substantially as specified.

SIGMUND BERGMANN.
